UNITED STATES PATENT OFFICE.

NORMAN B. HURD, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

FRICTION DOOR HOLDER.

Application filed August 1, 1925. Serial No. 47,440.

My invention relates to a door holder.

Door holders are now in use involving a pair of arms, one to be secured to a door casing and the other to be secured to a door or to a door closer thereon, which arms are pivotally connected together and so formed and arranged as to hold a door in open position. When such a door holder is arranged for a right hand opening door and it is desired to employ the same on a left hand opening door, it is necessary to turn the door holder upside down and often to make other changes in the arrangement of connections, etc.

It is an object of my invention to provide a door holder which may be used on either a right or left hand opening door and which need not be inverted when changing from a right to a left hand opening door.

It is a further object to provide a generally improved and novel form of door holder which may be readily adjusted for holding a door in substantially any desired position. Other minor objects will be apparent as the specification proceeds.

Briefly stated, in the preferred form of my invention, I employ a pair of arms, one to be attached to a door casing and the other to be attached to a door or a door closer thereon. The arms are pivotally secured together and a member, which I will term a friction block, is interposed between the pivotally secured arm ends. Means preferably including right and left hand screw threaded members serve to cause the friction block to engage one or the other of said arms, depending upon whether the device is used on a right or left hand opening door, and suitable means are provided for non-rotatably securing the friction block to one or the other of said arms.

In said drawings which illustrate merely a preferred form of the invention—

Fig. 1 is an isometric view of a door holder applied and illustrating features of the invention;

Fig. 2 is an enlarged fragmentary plan view of a door holder, as shown in Fig. 1, the arms being in alignment with each other;

Fig. 3 is a side view in partial section of the parts shown in Fig. 2.

In said drawings, 5 indicates an arm which may be pivotally secured to a door

casing 6, while 7 indicates a second arm 55 which may be pivotally secured to a door 8 or a door closer 9 secured thereto. The arms are pivotally secured together as is usual in door holders of this type. In the preferred form, I provide each arm with a 60 friction face 10 or engagement with a corresponding friction face formed on a member 11, which I will term a friction block, preferably interposed between the two arms. 65

A member such as a bolt 12 is preferably nonrotatably held on the arm 5 as by means of a square or other angular face 13 fitting a correspondingly formed bore in the arm. A nut 14 may be threaded on the 70 outer end of the bolt 12 so that the latter may be moved longitudinally and held in the bore in the arm 5. The inner end of the bolt 12 is preferably provided with a left hand thread 15 which engages a correspondingly formed thread in a part of the friction block 11. A second bolt 16 may be a substantial duplicate of the bolt 12 and is held in the opposite arm 7. The bolt 16, however, is provided with a right hand 75 thread 17 engaging a correspondingly threaded portion in the opposite side of the friction block 11. A nut 18 on the outer end of the bolt 16 may serve to position the bolt 16 longitudinally in the bore of the 80 arm in one direction, as previously described in connection with the bolt 12.

The friction block 11 is designed to be non-rotatably held to either of the arms alternately so as to cause the block and one 90 arm to rotate together so that when the arms are spread or swung relatively to each other, the friction block will ride on either the right or the left hand thread and cause the block to engage the friction face 10 on either 95 one or the other of said arms. In the form shown, I provide a bore or seat 19 in one arm and a corresponding bore 20 in the opposite arm. The friction block may have a projecting lug 21 thereon, having a bore 100 therethrough of substantially the same size as the bores 19—20. A pin 22 is adapted to pass through the bore in the friction block and into the bore 19 or alternately into the bore 20. The three bores 19—20, and the 105 corresponding bore in the friction block 11 are so arranged as to be in registry with each other when the three members having these

bores are in proper rotative position as shown in Figs. 2 and 3.

The operation of the device is as follows:

Assuming the parts to be substantially in the position shown in Fig. 3, it will be clear that the friction block 11 will be caused by the pin 22 to rotate with the upper arm 5. Now when the arms 5 and 7 are spread or swung relatively to each other, the friction block 11 will rotate relatively to the bolt 16 carried by the arm 7, and will contact with the friction face 10 on the arm 7, when the arms are swung in the proper direction and to the necessary extent. This frictional engagement of the block 11 and the friction face 10 on the arm 7, will be sufficient to hold a door in the proper position of adjustment.

Now, if the device is to be used on a door which swings in the opposite direction, it will not be necessary to invert the device but the holder may remain in the same upright position, the only change necessary being to move the arms relatively to each other so as to cause the bores 19—20 and the corresponding bore in the friction block 11 to come into registry with each other and then force the pin 22 down into the bore 19 so as to cause the friction block 11 to be non-rotatably secured to the arm 7. In the bottom of each bore 19—20, I preferably provide an aperture 23 so as to permit the use of a thin instrument for driving the pin 22 from the bore 20 to the bore 19, and vice versa. Now when the pin 22 holds the friction block 11 non-rotatably on the arm 7 and the arms are then again swung relatively to each other but in the opposite direction from that heretofore described, it will be clear that the friction block 11 will be caused to engage the friction face 10 on the arm 5 and thus hold the door in the proper position of adjustment.

When it is desired to vary the position at which the door is held open, it is only necessary to alter the position of the nut 14 or 18, depending upon whether the device is employed on a left or right hand opening door, so as to cause the space between the friction block and the corresponding arm to be greater or less. When this space is relatively small, the door will be held only slightly open. On the other hand, when this space between the friction block and arm is relatively greater, the door may be held open to a greater extent.

It will therefore be seen that with a door holder of the character described, it is not necessary to make any substantial alterations nor to invert the entire door holder when the same is to be used on either a right or left hand opening door. The change or alteration necessary involves only the sliding of a pin or the like from one arm into the other. The door holder may be readily and quickly

adjusted for holding the door in substantially any predetermined position of adjustment.

While the invention has been described in some detail, I do not wish to be strictly limited to the form shown since changes may be made within the scope of the invention as defined in the appended claims.

I claim—

1. In a door holder, a pair of pivotally connected arms, one to be attached to a door casing and the other to be attached to a door, a friction block interposed between said arms, means for non-rotatably securing said friction block to one arm when the door holder is to be used on a right hand opening door, and for attaching said friction block to the opposite arm when the door holder is to be used on a left hand opening door, and means for causing said friction block to frictionally engage one of said arms, all of said parts being non-yielding.

2. In a door holder, a pair of pivotally mounted arms, a friction block for engaging one of said arms, and means for causing said block and arm to frictionally engage each other when said arms are swung relatively to each other for holding a door in predetermined position, all of said parts being non-yielding.

3. In the combination defined in claim 2, and means for varying the position at which the door is held.

4. In a door holder, a pair of arms, a friction block between said arms adapted to frictionally engage one of said arms, means for securing said friction block non-rotatably to one of said arms, and screw threaded means for causing said friction block to frictionally engage one of said arms when the arms are swung relatively to each other, all of said parts being non-yielding.

5. A door holder, a pair of arms, a friction block interposed between said arms, screw threaded means for causing said block to move relatively to said arms, and a pin for securing said block against rotation on one of said arms, all of said parts being non-yielding.

6. In a door holder, a pair of arms, a friction block interposed between said arms, screw threaded means for pivotally securing said arms together and causing said block to move relatively to said arms to frictionally engage one or the other of the same alternately when the arms are swung relatively to each other, and means for securing said block non-rotatably to one of said arms, all of said parts being non-yielding.

7. In the combination defined in claim 6, and means for varying the position at which the friction block engages said arms.

8. A door holder, a pair of arms, a friction block interposed between said arms, a member having a right hand thread engag-

ing in a correspondingly formed thread in said block, said member being non-rotatably secured to one of said arms, a second member having a left hand thread non-rotatably secured to the other of said arms and engaging a correspondingly threaded portion in said block and means for non-rotatably securing said block to said arms alternately, whereby when said block is secured to one of said arms and the arms swung relatively to each other, the friction block will contact with one arm and when said friction block is secured to said other arm, said friction block will frictionally engage the opposite arm whereby said door holder may be used for holding either a left or right hand opening door, all of said parts being non-yielding.

9. In a door holder, a pair of arms, a friction block interposed between said arms, a member non-rotatably secured to one arm and having a right handed thread screwed into said friction block, a second member non-rotatably arranged in the other arm and having a left handed thread screwed into said friction block, said arms and block having pin seats registering with each other when said arms and block are in one position, and a pin engaging in the seat of said friction block and adapted to engage the seats in said arms alternately whereby when said pin secures said block to one arm non-rotatably, said friction block and one arm will frictionally engage each other to hold the arms in one position and when said pin secures said friction block to the other arm, said friction block will be caused to engage one of the arms for securing said arms in a different relative position.

NORMAN B. HURD.
